UNITED STATES PATENT OFFICE.

ALMON E. NORRIS, OF CAMBRIDGE, MASSACHUSETTS.

POWER-OPERATED DRUM OR WINCH APPARATUS.

SPECIFICATION forming part of Letters Patent No. 774,449, dated November 8, 1904.

Application filed March 5, 1903. Serial No. 146,265. (No model.)

To all whom it may concern:-

Be it known that I, ALMON E. NORRIS, a citizen of the United States, residing at Cambridge, in the county of Middlesex and State 5 of Massachusetts, have invented an Improvement in Power-Operated Drum or Winch Apparatus, of which the following description, in connection with the accompanying drawings, is a specification, like letters on the drawings representing like parts.

The object of my invention is to provide an improved compact drum or winch apparatus for winding and unwinding cables.

My invention is particularly applicable to 15 an apparatus designed for use in swinging a derrick, wherein the motor speed should be maintained sufficiently high to permit of ready and complete control and by operating through suitable reduction-gears upon the 20 winch or drum produce a relatively slow swinging movement of the derrick.

Furthermore, my invention aims to provide 25 novel friction holding means to enable the derrick when necessary to give or yield sufficiently to avoid damage—as, for instance, when a load carried thereby is suddenly diverted or moved to one side against the power of the motor tending to hold it or move it in an opposite direction.

30 To enable my invention to be understood, I will describe the same in connection with the best embodiment thereof known to me, it being understood, however, that my invention is not restricted to the embodiment illustrated.

35 In the accompanying drawings, Figure 1 is a side elevation of an apparatus, illustrating one embodiment of my invention. Fig. 2 is a top or plan view of the apparatus shown in Fig. 1. Fig. 3 is a vertical cross-section on the dotted line 3 3, Fig. 2. Fig. 4 is a vertical longitudinal section on the dotted line 4 4, Fig. 2; Fig. 5, a horizontal section through the throttle-valve; and Fig. 6, a vertical section of the valve, Fig. 5.

40 In the particular embodiment of my invention selected for illustration herein and shown in the drawings, A is the bed, of suitable shape and construction to carry the various parts of the apparatus. Upon this bed, as herein 45 shown, are mounted at opposite sides and at

one end the cylinders C C of the engines, which are herein employed for furnishing the power with which to operate the apparatus. These cylinders contain pistons mounted upon the piston-rods c, carrying cross-heads c', 55 which reciprocate upon the bar-guides c", suitably mounted upon the bed. The wrist-pins c" of the cross-heads are connected by usual connecting-rods c' with the crank-pins c" on usual cranks c", fast upon the engine crank-shaft c', mounted to rotate in suitable bearings upon the bed. Eccentrics c", fast upon the crank-shaft, operate through suitable eccentric-rods c' to actuate the valves within the steam-chests C', and since the engines are reversed by the throttle-valve, but a single eccentric is required for each engine.

Fast upon the crank-shaft c' is a spur-pinion d, which meshes with and drives a large spur-gear d', fast upon the winch-shaft d", 70 journalled in suitable bearings upon the bed.

Loosely sleeved upon the winch-shaft d" is the winding drum or winch D, herein shown as a winch, about which the operating-cable k is wound. At one of its ends the winch D 75 (see Figs. 3 and 4) carries the diametrically-arranged studs d", upon which are loosely mounted the toothed wheels d", which at their inner adjacent sides mesh with a common spur-gear d", fast on the winch-shaft d", and at 80 their outer sides said gears d" mesh with a common internal gear d", formed upon or at the inner flange-face of a friction member e, loosely mounted upon the winch-shaft d".

Encircling the flanged member e is a friction-band E, (see Figs. 2, 3, and 4,) said band having its ends oppositely extended and crossed at the under side of said flanged member and secured in suitable manner, as by the nuts e', threaded thereon and seated against suitably-formed portions of the bed-plate. Obviously any attempt to rotate the flanged member e in either direction will tend to wrap the friction-band E about and upon it, and thereby lock the said flanged member frictionally 95 against rotation. With said flanged member e so held rotation of the winch-shaft d" by the engine in either direction will operate through the gears d" d" and the internal gear d", which severally constitute an embodiment of the 100

well-known planetary gear, to rotate the winch D in the same direction, but at a greatly reduced speed, the speed reduction depending, of course, upon the ratio of gearing. With the cable k connected with and to swing a derrick it is evident that operation of the engine in one or the other direction will thus operate to swing the derrick slowly always in a corresponding direction.

10 The apparatus is self-contained—that is, the winch speed-reducing and friction holding mechanism or device are arranged wholly within the limits required for the double engine which operates the same.

15 Referring now to Figs. 5 and 6, I will describe the preferred form of means for reversing the engine. Live steam is admitted through the pipe o, and the exhaust is discharged from the pipe o'. Between the live-20 steam inlet and the exhaust the valve-casting O is provided at each of its opposite sides with two outlets, with which are connected, respectively, the pipes o² and o³, leading to the steam-chest of the engine-cylinder at that particular 25 side of the valve. Each engine is provided with a usual piston or other valve device of well-known construction, whereby when steam is admitted, say, at the ends of the valve the engine will operate in one direction, and when 30 admitted, say, at the middle of the valve the engine will operate in a reverse direction. Consequently one of these pipes, as o³, leads to the outside or ends of the valve and the other, as o², to the inside or middle of the valve, so 35 that if steam be admitted through the pipes o² to the respective cylinders the engines will operate in one direction, and if steam be admitted through pipes o³ to the same cylinders the engines will operate in a reverse direction, the 40 live steam and exhaust in each case entering and leaving through the pipes o and o'. The throttle-handle o⁴ is mounted upon the end of the throttle-valve stem o⁵, which latter within the valve-casting is slotted diametrically to receive the rectangular lugs p of two of the oppositely-facing D-valves p'. Referring particularly to Fig. 5, the exhaust-port at each side of the valve-casing is arranged between the live-steam ports x' and x², which latter are 45 connected, respectively, with the pipes o² and o³, so that as the throttle-valve stem is turned in one or the other direction it will cause its D-valves p' to be positioned to admit live steam to one of the ports x' or x² and place 50 the other of said ports in communication with the exhaust, and the particular ports x' or x² and pipes o² and o³ through which live steam is admitted, determine, of course, the direction of operation of the engine. Thus the 55 engineer by a single throttle-lever may start and stop the engine, determine its direction of movement and its rate of speed, thereby simplifying the operation of machines of this type. The derrick when swinging may be 60 quickly stopped by reversal of the engine, 65

the frictionally-held member e yielding sufficiently to take up any shock, which might otherwise prove detrimental. In the throttle the valves p' are free to move radially in the holding-slot of the throttle-stem, thus permitting the steam-pressure within the throttle-casing to maintain the said valves tightly pressed against their respective seats precisely as with the ordinary slide-valve of a steam-engine. This eliminates all the difficulties, of which the sticking of the valve is one, which result from the use of a valve in the form of a taper core. With the construction here shown the valve always operates easily, yet remains under all conditions perfectly tight—in fact, it wears itself to a tight fit.

70 Claims to the features of novelty of my improved valve herein described are embodied in my application, Serial No. 228,253, pending 75 concurrently herewith.

80 My invention is not restricted to the specific embodiment thereof here shown and described, but may be varied within the spirit and scope of the invention.

85 I claim—

1. A winding apparatus comprising a drum or winch and speed-reduction driving means therefor including a yieldable thrust-resisting member.

and having its ends oppositely extended and secured, to hold the said member frictionally against movement in opposite directions.

9. A winding apparatus comprising a winding-winches, a reversing-motor and speed-reduction driving-gearing between said motor and said winch, and a double-acting yieldable friction holding device in connection with which said speed-reduction gearing operates.

10. 10. In a winding apparatus, a power-driven shaft, a drum or winch shaft geared thereto, a winch loosely mounted on said shaft and connected with the latter by speed-reduction gearing, and means to hold through yielding 15 frictional contact, one of the elements of said speed-reduction gearing.

11. In a winding apparatus a power-driven shaft, a winch-shaft geared thereto, a yieldably-held friction-controlled member loosely 20 mounted on said shaft, a winch also mounted loosely on said shaft, and speed-reduction gearing interposed between said winch and shaft and including the said frictionally-held member for operating said winch at a reduced 25 speed from the shaft on which it is mounted.

12. A winding apparatus comprising a power-driven shaft and means including a single, manually-operated, handle or member for rotating the said shaft in opposite directions at will, a winding-winches, and speed-reduction gearing including an element yieldably and frictionally held against movement in either direction for operating said winch from said shaft in one or the other direction, 35 according to the direction of rotation of said shaft.

13. A winding apparatus comprising an engine, a throttle device to start, stop, reverse and determine the speed of said engine, a winding-winches and speed-reduction gearing interposed between the same and the crank-shaft 40

of said engine and including an element, yieldably and frictionally held against movement in either direction for operating said winch, from said engine, in the direction and at a speed, determined by said throttle or device. 45

14. A winding apparatus comprising an engine, a throttle device to start, stop, reverse and determine the speed of said engine, a winding-winches and speed-reduction gearing interposed between the same and the crank-shaft of said engine, and including an element yieldably frictionally held against movement in two directions, for operating said winch from said engine, in the direction and at a speed determined by said throttle handle or device. 50 55

15. In an apparatus of the class described, driving means, a load-moving element, suitable gearing and transmission means interposed between said driving means and said moving element, including a normally unyieldable transmission member provided with means permitting the yielding thereof on abnormal power-transmitting conditions. 60

16. In an apparatus of the class described, driving means, a load-moving member and suitable gearing and transmission means interposed between said load-moving element and said driving means, including a transmission member provided with a friction-band 70 adjusted normally to oppose movement of said transmission member but permitting movement thereof on abnormal power-transmitting conditions. 75

In testimony whereof I have signed my name to this specification in the presence of two subscribing witnesses.

ALMON E. NORRIS.
